DRAFT ROLL

Edward J. Abbott, Wilton, N. H., assignor to
 Abbott Machine Company, Wilton, N. H., a cor-
 poration of New Hampshire

Application October 15, 1930. Serial No. 438,690

1 Claim. (Cl. 19--115)

This invention relates to draft roll mechanism for textile machines and is of particular applicability in textile machines which handle textile fibers (for instance unspun "sliver"), in connection with a drafting or drafting and combing operation performed thereon. Objects of the invention are to provide a draft roll construction capable of improved operation and with which the combing or other fiber-handling mechanism may react on the fibers at a point relatively close to the bite of the rolls, wherein mutilation of the endless apron usually employed in connection with one of the rolls is avoided, wherein the draft roll mechanism is enabled to draw the fibers in a uniform manner regardless of the condition of wear of the endless apron, and wherein the draft rolls may be of small diameter.

Other objects of the invention, advantages and structural improvements will appear from a consideration of this explanation of a typical instance of the invention shown by way of example in the accompanying drawing.

In the drawing:

Fig. 1 is a side elevation, partly in section, of a textile machine for combing unspun fibers and guiding the fibers onto a winding spool;

Fig. 2 is an elevation of parts of the device of Fig. 1 looking in the direction of the arrows 2-2 of Fig. 1; and

Fig. 3 is a diagrammatic view of driving connections of the device.

Fig. 4 is a fragmentary view corresponding to Fig. 2, showing a modified form of lower roll.

The improved draft roll construction of the present invention is shown by way of example in Fig. 1 as embodied in a textile machine operating on a strand of sliver which passes to the draft roll mechanism between corrugated rolls 11 and 12 on its way from a condenser or other sliver-handling equipment. A pair of opposed draft rolls 13 and 14 is provided for the purpose of drawing the sliver. The illustrated machine is shown as having combing means disposed to react on the sliver, and herein shown at 15 as of a conventional type comprising moving fallers which rise, move generally with the strand of sliver toward the draft rolls but at a slower rate, descend out of contact with the sliver, and return to their initial position.

After passing between the draft rolls 13 and 14, the combed sliver passes through a trumpet guide 17 which may be of the rotary type, and from thence onto a winding spool 18, herein shown as frictionally driven by a driving drum 19. Suitable traverse mechanism, not shown, may pro-

vide relative back and forth movement of the spool 18 with respect to the trumpet 17.

Referring to Fig. 3, the driving drum 19 may be mounted upon a shaft 20 which is suitably driven and which serves to drive the lower draft roll 14 through suitable gearing diagrammatically indicated at 21.

The upper draft roll is shown as mounted on an elevated frame 25 suitably secured to the machine and carrying generally vertical guide rods 26 on which housings 27 for the roll are adapted to slide. Pressure means is provided for loading the upper roll, causing it to bear heavily upon the sliver, this pressure means being preferably constituted, as shown, of strong springs 28, bearing at their lower ends against the housings 27 and at their upper ends against adjusting nuts 30.

The upper draft roll 13 is preferably embraced by an endless apron 23, of leather or other suitable somewhat resilient material which turns with the roll and is adapted to cushion the sliver and prevent its being cut by the rolls, such apron being a well known and usual element in devices of this type. This apron runs beneath roll 13, and upon an auxiliary roll 24 suitably supported by the elevated frame 25, the sliver, as it passes between the draft rolls, being engaged by the lower draft roll and the endless apron 23. Referring to Fig. 2, the device may be adapted to draw a plurality of strands or groups of strands of sliver through separate sets of fallers, and in this instance the upper draft roll 13 may be provided, as shown in Fig. 2, with a plurality of endless aprons 23, and may be reduced in diameter between these endless aprons.

In devices having general arrangements as described above, it has been customary to provide the draft rolls corresponding in position to draft rolls 13 and 14 of the present device with deeply corrugated surfaces so that the upper draft roll, together with an endless apron running thereon, would mesh with the lower draft roll and be positively driven thereby. This has necessarily resulted in mutilation of the endless apron which runs between the draft rolls. As the endless apron would wear in use it would enter more deeply into the corrugations of the intermeshing draft rolls and as a consequence cause the sliver to follow more nearly the contour of these corrugations. This has resulted in increasing the rate of drawing the sliver as the endless apron became worn, thus altering the ratio of speed of the sliver with respect to that of the fallers, and therefore causing uneven drafting of the sliver.

To avoid this difficulty, smooth draft rolls might be employed. However, for the upper roll to be driven frictionally by the lower roll, as distinguished from the usual positive drive, such an upper roll, substituted in previous devices, would need to be of large diameter to obtain sufficient tractive effort from the lower roll to turn against the loading pressure of the springs 28. The use of such an upper roll of large diameter would be inadvisable since it would prevent the fallers from approaching close to the bite of the rolls and hence would allow short fibers to leave the fallers before being caught by the draft rolls resulting in a defective product. Furthermore, many existing machines, now equipped with small corrugated rolls, could not have smooth rolls of large diameter substituted therein, because of the structural limitations of the environment of the rolls.

In the machine of the present invention, these difficulties are avoided by the provision of upper and lower draft rolls 13 and 14 of small diameter so that the fallers 15 may approach close to the bite of the rolls, and the provision of anti-friction bearings for the upper roll 13, so that this roll may readily be frictionally driven regardless of the necessary loading pressure exerted thereon. Such anti-friction bearings are herein illustrated as roller bearings 32 disposed within a suitable race 33 in the upper roll 13. With this improved arrangement of the upper roll, the lower roll 14 may also be substantially a plain cylinder as shown in Fig. 1, instead of corrugated as has been customary. The apron 23 is thus not mutilated in passing between the rolls, is subject to less wear, and does not cause any substantial change in the rate of drafting the sliver upon wearing thin.

The cylindrical surface of the lower or positively driven roll is preferably roughened to an extent which facilitates the traction of the roll with respect to the fibrous strand but not sufficient to cause any substantial mutilation or distortion of the endless apron or equivalent cushioning part. Thus in Fig. 2, the lower roll 14 is shown as provided with narrow flutes 35, which may be for example of the order of 0.1 inch in width and of similar depth, to insure a better grip

upon the sheet of sliver. These flutes which are preferably provided only on the lower or positively driven roll, should be of such small dimension that the sliver engaging surface of the apron 23 is not caused to be distorted thereby, as distinguished from the larger corrugations in which the aprons of previous devices were intended to mesh.

In the alternate form of construction of Fig. 4, the lower or positively driven roll 14 is shown as having its cylindrical surface covered with a hard, granular material 35' such as is commonly used as an abrasive, for example, carborundum. This material likewise affords improved frictional contact between the roll 14 and the fibrous strand.

While in the illustrated device the fibrous strand is shown as cushioned by the endless apron 23, it will readily be apparent that for this purpose the apron may in some instances be replaced by a covering of cork, leather, parchment or other somewhat resilient cushioning material fast on the surface of the corresponding draft roll. Either the apron or cushioning surface on the upper roll, is useful also in providing better frictional engagement with the textile fibers being drafted, thus to prevent slippage of this upper roll with respect to the fibers.

It should be understood that the present disclosure is for the purpose of illustration only and that this invention includes all modifications and equivalents which fall within the scope of the appended claim.

I claim:

Silver drawing mechanism comprising in combination, upper and lower substantially cylindrical draft rolls of the approximate diameter of the usual small intermeshed or positively geared draft rolls, loading means forcing said rolls together, gilling means in advance of said rolls and located closely adjacent to the nip point, said rolls being free from intermeshing action or positive driving of one by the other, means for driving one of said rolls, and anti-friction bearings for the other of said rolls permitting said latter roll to be driven through the intermediary of the sliver, the mechanism including cushioning means embracing one of the rolls.
